Des. 202,915
Patented Nov. 16, 1965

202,915

STEAK MARKER

Donald C. Nelson, 3882 Brywood Road,
Akron 13, Ohio

Filed Jan. 8, 1965, Ser. No. 83,334

Term of patent 14 years

(Cl. D44—29)

FIG. 1

FIG. 2

FIG. 1 is a front elevational view of a steak marker showing my new design; and

FIG. 2 is a side elevational view.

The rear face, not shown, is substantially plain and unornamented.

The essential features of my design are shown in full lines on the drawing.

I claim:

The ornamental design for a steak marker, as shown and described.
